US0D1049523S

(12) **United States Design Patent** (10) Patent No.: **US D1,049,523 S**
 (45) Date of Patent: ** Oct. 29, 2024

(54) **PORTABLE STEAMER**

(71) Applicant: **SHEN ZHEN RONE PHOENIX
NEST DESIGN DEVELOPMENT
CO., LTD**, Guangdong (CN)

(72) Inventor: **YongJie Yi**, Guangdong (CN)

(73) Assignee: **SHEN ZHEN RONE PHOENIX
NEST DESIGN DEVELOPMENT
CO., LTD.**, Shenzhen (CN)

(**) Term: **15 Years**

(21) Appl. No.: **29/868,541**

(22) Filed: **Dec. 6, 2022**

(51) LOC (14) Cl. **15-05**

(52) U.S. Cl. **D32/17**
USPC .....

(57) **CLAIM**

The ornamental design for a portable steamer, as shown and described.

DESCRIPTION

FIG. 1 is a bottom, front, right side perspective view of a portable steamer, showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines show features of the portable steamer that form no part of the claimed design.

1 Claim, 7 Drawing Sheets
